PEDESTAL ANTENNA

Raymond A. Rosenberry, 1501 Superior Bldg., Cleveland,
Ohio 44113, and Wilbur W. Wilhelm, 9208 Behrwald
Ave., Brooklyn, Ohio 44142

Filed Mar. 8, 1967, Ser. No. 6,126

Term of patent 14 years

(Cl. D26—14)

FIG. 1

FIG. 3

FIG. 2

FIG. 4

FIG. 1 is a view in front elevation of a pedestal antenna embodying the design of our invention and showing a selected position of the movable front escutcheon plate.

FIG. 2 is a view in rear elevation of the design shown in FIG. 1 and showing a selected position of the movable rear plate.

FIG. 3 is a view in side elevation of the design shown in FIG. 1, as viewed from the right side thereof.

FIG. 4 is a perspective view of a pedestal antenna embodying the design of our invention and showing an alternative position of the movable front escutcheon plate and an alternative position of the movable rear plate.

We claim:

The ornamental design for a pedestal antenna, substantially as shown and described.
